(57) **CLAIM**

The ornamental design for a shoe bottom cleansing apparatus, as shown and described.

DESCRIPTION

FIG. 1 is a top perspective view of a shoe bottom cleansing apparatus illustrating my new design;

FIG. 2 is a top plan view thereof;

FIG. 3 is a bottom plan view thereof;

FIG. 4 is a left side elevation view thereof;

FIG. 5 is a right side elevation view thereof;

FIG. 6 is a rear elevation view thereof; and,

FIG. 7 is a front elevation view thereof.

Broken lines illustrate portions of the shoe bottom cleansing apparatus that form no part of the claimed design.

1 Claim, 5 Drawing Sheets
